UNITED STATES PATENT OFFICE

FRANCIS M. BARTON, OF CHICAGO, ILLINOIS, ASSIGNOR TO BARTON SPIDER WEB SYSTEM, OF CHICAGO, ILLINOIS, A CORPORATION OF ILLINOIS

METALLIC LATHING

Application filed October 21, 1926. Serial No. 143,063.

The invention relates to metallic lathing.

One object of the invention is to provide an improved lath formed of a metal sheet which is continuously corrugated, so that the sheet as a whole will possess the strength of a uniformly corrugated sheet with integral plaster retaining tongues disposed in the grooves on the outer face of the sheet. Other objects of the invention will appear from the detailed description.

The invention consists in the several novel features hereinafter set forth and more particularly defined by the claim at the conclusion hereof.

15 In the drawing: Fig. 1 is a perspective of a portion of a sheet of lath embodying the invention. Fig. 2 is a section, showing the lap between two sheets of lath. Fig. 3 is a plan of the lath, the back face being shown.

20 Fig. 4 is a section on an enlarged scale, showing the plaster on the lath.

The invention is exemplified in a sheet of metal 5 which is corrugated throughout its entire area. The corrugations extend from 25 end to end of the sheet. The latter may be of any desired size. The sheet comprises a series of curved crown portions 6 at the outer face of the sheet which are united by a series of reversely curved crown portions 7 at the inner face of the sheet. The portions between the outer portions of the crowns 6 consist of 30 portions 8 and 9 which extend transversely to the plane of the sheet to form a parallel series of outwardly flared grooves 10 on the outer

35 face of the sheet and alternating series of similar oppositely flared grooves 11 on the inner face of the sheet. The side portions 8 are cut, as at 12, to leave integral out-struck tongues 13 which are bent transversely into 40 the grooves 10 to form plaster retaining claws. The side portions 9 are similarly cut to form tongues 14 which are also bent away from said sides and into the grooves 10 to form plaster retaining claws. The tongues

45 13 are formed at points which are staggered or out of line with the tongues 14 on the opposed side portion 9, so that each tongue will be disposed opposite an imperforate portion 15 of the opposite side of each groove 10.

50 Tongues 13 and 14 are bent and curved to-

ward each other sufficiently to render them efficient in holding the plaster in the groove 10. The openings 16, left from cutting the tongues, permit the plaster to pass laterally into the back of the crowns 6 from the side portions so as to form an efficient lock between the plaster and the crowns of the sheet, as shown in Fig. 4. As a result of this formation, there is a continuous longitudinal zone of metal at the outer portions of the crowns 6 and 7 which will give to the sheet the desired rigidity and strength, notwithstanding the cut-away portions. In practice, one margin of the sheet is left uncut, as at 20, and without tongues, so that it may be lapped by 65 the margin of another sheet. Any suitable means may be used to secure the sheet in place.

The invention exemplifies a metallic lath which is formed of a sheet of metal which is 70 corrugated throughout its entire area to render it of unusual stiffness and strength so that this metal will suffice. The lath is especially advantageous in ceilings on the underside of concrete floors, as well as in 75 other places where the load of the plaster is suspended from the lath.

When so used, it provides a structure in which the crown portions 6 will be under tension and the crown portions 7 will be under 80 compression. The tongues 13 are curled sufficiently to form effective keys for the plaster and the openings 16 permit the plaster to pass in back of the crowns 6 and the sides 8 and 9. The outer ends of the claws or tongues 13 and 85 14 are substantially coincident with the plane of the outer crowns 6 or slightly inside of it, so that the tongues will not interfere with the application of the plaster to the sheet, such as occurs when the retaining tongues project 90 from the plane of the outer face of the sheet.

The invention is not to be understood as restricted to the details set forth, since these may be modified within the scope of the appended claim, without departing from the 95 spirit and scope of the invention.

Having thus described the invention, what I claim as new and desire to secure by Letters Patent, is:

A metallic lath consisting of a sheet of 100

metal having a substantially continuous series of parallel corrugations extending across it and comprising alternating series of crowns at opposite faces of the sheet and side portions extending transversely between the crowns, and tongues struck wholly from the side portions, said tongues being connected at one end thereof to the sheet adjacent one series of crowns and having their other ends bent into the grooves between the other series of crowns and terminating inwardly of and adjacent the plane of said other series of crowns, both series of crowns being imperforate and continuous.

15 Signed at Chicago, Illinois, this 10th day of May, 1926.

FRANCIS M. BARTON.
